UNITED STATES PATENT OFFICE.

GIOVANNI EMANUELE ELIA, OF NEW YORK, N. Y.

DEVICE FOR PROTECTING SHIPS AGAINST SUBMARINE EXPLOSIONS.

1,246,073.

Specification of Letters Patent. Patented Nov. 13, 1917.

Application filed January 15, 1917. Serial No. 142,443.

To all whom it may concern:

Be it known that I, GIOVANNI E. ELIA, a subject of the King of Italy, residing in the city of New York, county of New York, 5 and State of New York, have invented certain new and useful Improvements in Devices for Protecting Ships Against Submarine Explosions; and I do hereby declare the following to be a full, clear, and exact 10 description of the invention, such as will enable others skilled in the art to which it appertains to make and use the same.

This invention relates to a device for protecting ships against submarine explosions.

15 An object of the invention resides in the provision of a device which is buoyant and will conform to the sides of a ship and which is formed of such material that the shock of the explosion will be taken up entirely thereby.

20 A further object of the invention resides in so constructing the device that it will float, and when engaged by the bow of a ship, will automatically, during the advance 25 of the ship, conform to and lie against the sides thereof continuously throughout their extent.

With these and other objects in view, such 30 as will appear as my description progresses, my invention comprises a combination and arrangement of parts as set forth in and falling within the scope of the appended claims.

In the drawing:—

35 Figure 1 is a plan view of a ship showing a device constructed in accordance with my invention in place thereon;

Fig. 2 is a side elevation thereof;

40 Fig. 3 is a transverse sectional view through the ship showing the relation of the protective device to the sides thereof; and

Fig. 4 is a similar view disclosing a modified form of the device.

In the drawing, I have illustrated, conventionally, a ship 1 to which my device is applied. The protective device 2 extends continuously around the sides of the ship from bow to stern, and comprises a plurality of cables, 3, of manila or similar material, 45 each of which is equal in length to the entire length of the protective device and which are arranged side by side, as illustrated in Fig. 3 of the drawing. These Manila cables are bound together by encircling linen 50 or steel cables 4, as illustrated in Figs. 1 and 2 of the drawing, so that they form, in

effect, an elongated bundle. The cross-sectional shape of this bundle is such that it will lie against the sides of the ship and extend at least to the bottom thereof and a 60 suitable distance above the water line. The density of the protective device is preferably approximately the same as that of the water of flotation, so that the device will float and so that when a portion thereof is blown 65 away by a submarine explosion, the position of the device in the water will not be altered as the water rushes into such portion.

In Fig. 4 of the drawing, I have illustrated a somewhat modified form of the 70 device, which, instead of being completely formed of Manila cables bound together, is provided with one or more wooden frames 5 which are disposed within the device longitudinally, but terminate so as to permit 75 the flexing of the device midway between its ends, that is, at the point where it engages the bow of the ship. These frames are surrounded by Manila cables 6 arranged in a manner similar to that in which those in 80 the form shown in Fig. 3 are arranged, and these Manila cables are bound together in a similar manner by encircling linen or steel cables 7.

The device is used in substantially the 85 same manner as the protective device described and claimed in my co-pending application, Serial No. 138,408, filed December 22, 1916, that is to say, that it floats in the water with its long dimension arranged vertically, and so that when it is desired to envelop the ship therewith, it is only necessary for the ship to advance until the bow engages the device midway between its ends and to continue this advance until the device is swung into contact with the sides of the ship in such a position as illustrated in Fig. 1 of the drawing. It is to be understood that this protective device may also be towed in the manner described in the co-pending application referred to, by the ship itself or by a plurality of paddle tug boats, in which latter event, it will, in conjunction with a plurality of similar devices, inclose 90 and protect an area in which otherwise unprotected ships may be operated.

It will be obvious that this device may be maintained upon the ship in rough weather, because of the fact that it is formed of Manila cables or other soft materials, and is, therefore, flexible in all directions, so that 100 it will rise and fall under the action of the 105

waves. Because of this fact, the device is particularly advantageous and will be exceedingly convenient to use.

What I claim is:—

- 5 1. A protective device for ships consisting of a continuous fibrous element adapted to envelop the sides of a ship, and binding elements encircling the same.
- 10 2. A protective device for ships consisting of a floatable member comprising a plurality of individual fibrous elements arranged side by side and extending continuously from end to end of the device, and means for binding said elements together.
- 15 3. A protective device for ships consisting of an elongated member including a plurality of individual fibrous elements ar-

ranged side by side, and cables binding said elements together.

4. A protective device for ships consisting of a flexible member including a plurality of individual fibrous elements arranged in superimposed relation, and binding cables passing around and binding said elements together.

5. The combination with a ship, of a protective device therefor enveloping the sides thereof, which device consists of a plurality of flexible fibrous elements arranged side by side and continuous from end to end of the device, and cables binding said elements together.

In testimony whereof I affix my signature.
GIOVANNI EMANUELE ELIA.
